ISAAC A. SHEPPARD, OF PHILADELPHIA, PENNSYLVANIA.

Design No. 3,583, dated July 13, 1869.

DESIGN FOR A STOVE-DOOR.

The Schedule referred to in these Letters Patent and making part of the same.

To all whom it may concern:

Be it known that I, ISAAC A. SHEPPARD, of Philadelphia, county of Philadelphia, State of Pennsylvania, have originated a new Design for a Stove-Door; and I do hereby declare that the accompanying drawing, and following explanation thereof, form a full, clear and exact description of the said design.

In the drawing, the figure represents my design for a stove-door.

Extending around the outer edge of the door is a plain beading, *a*, within which are the vertical panels *b b b b*, each of the latter containing a foliated ornament, *c*, of the character clearly represented in the drawing.

The central figure of the design consists of a shield, *d*, within which is the ornamented boss *f*.

I claim the design for a stove-door substantially as described, and as represented in and by the accompanying drawing.

In testimony whereof, I have signed my name to this specification, in the presence of two subscribing witnesses.

ISAAC A. SHEPPARD.
